CLAIM

The ornamental design for a beard trimmer with comb, as shown and described.

DESCRIPTION

FIG. 1 is a front elevational view of the present new design of a beard trimmer with a comb, with the comb rotated to a first position;

FIG. 2 is a top and front view of FIG. 1;

FIG. 3 is a bottom and rear view of FIG. 1;

FIG. 4 is a right side view of FIG. 1;

FIG. 5 is a left side view of FIG. 1;

FIG. 6 is a rear view of FIG. 1;

FIG. 7 is a rear perspective view of the present trimmer shown with the head and comb rotated to a second position (which is 180° from the first position);

FIG. 8 is a front view of FIG. 7;

FIG. 9 is a top and front view of FIG. 7;

FIG. 10 is a bottom and rear view of FIG. 7;

FIG. 11 is a right side view of FIG. 7;

FIG. 12 is a left side view of FIG. 7; and,

FIG. 13 is a rear elevational view of FIG. 7.
